UNITED STATES PATENT OFFICE.

HENRY C. SWAN, OF SWANVILLE, PENNSYLVANIA.

TOY WHISTLE.

SPECIFICATION forming part of Letters Patent No. 291,548, dated January 8, 1884.

Application filed June 4, 1883. (No model.)

To all whom it may concern:

Be it known that I, HENRY C. SWAN, a citizen of the United States, residing at Swanville, in the county of Erie and State of Pennsylvania, have invented a new and useful Toy Whistle or Device to Aid a Whistler in Producing Musical Sounds, of which the following is a full, clear, and exact description, when taken in connection with the accompanying drawings, forming a part thereof.

My invention relates to a device for whistling, or to aid the whistler in producing musical sounds in a clearer, better tone, and with much less exertion to the operator, than is required in whistling without the aid of my device; and to this end my invention consists of a block, disk, plate, or other suitable form, made of metal, glass, hard rubber, celluloid, wood, artificial ivory, or other suitable material, having an opening or hole therethrough, said opening or hole being so constructed that a person holding the device between his lips, or lips and teeth, or holding it to the mouth and blowing through it, can whistle the scale or tunes, trill, or make "calls," as these are ordinarily done by a good whistler with the lips only.

My invention consists, further, in certain details of construction, which will be fully described hereinafter, and pointed out in the claims.

Figure 1 is a side elevation. Fig. 2 is a view of the inner end, and Fig. 3 is a view of the outer end, of the whistle. Fig. 4 is a vertical sectional view in the line *x x* of Fig. 1. Figs. 5, 6, 7, 9, 11, 12, and 13 show modifications in the forms of construction, all tending to produce the same result. Fig. 8 is a sectional view, showing a thin disk introduced into the device shown in Fig. 7. Fig. 10 is a sectional view on line *y y* of Fig. 9.

A is the body of the whistle, which is made of glass, metal, hard rubber, celluloid, wood, artificial ivory, or other suitable material, and of a size and shape to be conveniently placed between the lips or lips and teeth of the operator. It may, however, be made of a size larger than would conveniently be received by the lips or lips and teeth, and be thus adapted to be placed against the lips when puckered,

as in the ordinary manner of whistling. The body of the whistle is provided with a diaphragm or partition, *a*, having a central hole or aperture, *c*, extending therethrough, the inner end of which opens out into an air-chamber, *g*, which acts as a pocket or cushion for the pressure of air from the lungs. The edges of said aperture where it enters the chamber *g* are clear cut and well defined, as shown at *o*, so as to produce a sharp angle at 55 the point where the air enters the aperture *c*, this form having been found to produce the best results. The outer end of the aperture *c* is beveled or flares outwardly, as shown at *d*, and opens or terminates in the flaring 60 mouth *h*, so as to permit the ready escape of the air in sound-waves with but little exertion to the operator, the tone, pitch, or sound produced being controlled by the muscular action of the tongue and throat, and the 65 volume of air passed through the opening *c*, as is done in the act of ordinary whistling.

In Fig. 5 I have shown the hole or opening *c* made of the same diameter throughout its entire length, but with a deeper bevel, *d*. 75 This form of construction will admit of a slight reaming or beveling of the inner orifice of the hole *c*, and breaks up the well-defined corner or sharp edge, as shown at *o*.

Fig. 6 shows another form of whistle, in 80 which the hole *c* is of the same diameter from the inner to the outer end.

In Fig. 7 I have shown a combination of the devices shown in Figs. 4 and 5, with the addition of a thin disk, *e*, (see Fig. 8,) having 85 an opening, *f*, through it, and closely fitted against the inner end of the hole *c*, the opening *f* being concentric with the hole *c*.

In Fig. 9 I show a double whistle, or two whistling or sound-producing openings combined in one block, disk, or plate, as shown in Fig. 10. I make the holes *c c* of different lengths and sizes, which has the effect of producing tones or sounds of different pitch and volume, and thus enables the operator to play 90 or carry two parts of a tune at one and the same time; or, by the same construction, I may combine two or more than two whistles by increasing the number of sound-producing apertures *c*, or by combining them with the 95 100

main opening in the block, as shown in Fig. 13, or by having separate openings, as shown in Fig. 10.

In Fig. 11 I have shown the application of my whistle to a horn or extended tube, which may be provided with holes or keys, and manipulated as in fifes, flutes, horns, or other wind-instruments, and the main advantage gained by this use of my device is that the heavy pressure on the lips by the instrument is obviated, as the puckering of the lips upon the whistle does not weary or strain the muscles of the lips, as is the case in producing sounds with the lips without this internal support. Furthermore, the sound is produced at a point where the lips come in contact with the sides of the whistle, and not within the tube or instrument, as is the case with the ordinary mouth-piece used in playing the fife or other wind-instrument.

In Fig. 12 I have shown still another modification, in which the outer and inner ends of the hole *c* are enlarged to a greater or less degree, and in which the inner end of the aperture *c* may be slightly enlarged by a beveled edge.

As before stated, Fig. 13 shows a compound whistle, in which any of the hereinbefore described forms of hole *c* may be used, said holes being of different sizes, to produce varying, different, or the same sounds, and opening into the air-chamber *g* in the inner end of the whistle.

I do not limit myself to the precise form or size or depth of the hole *c*, or to the contour of the device; but experiments have shown that a hole in which the length is a little less than the mean diameter produces the best results. The approximate diameter may be from three thirty-seCONDS to three-sixteenths of an inch, but may be varied without departing from the spirit of my invention; neither do I wish to limit myself to a toy whistle as the sole use to which my device can be put, as it is obvious that it can be applied to musical instruments, to the handles of canes, whips, and umbrellas. It can be applied to speaking-tubes as a call, and to other toys in which whistles are used, or be worn as a watch-charm or bangle.

The operation of my device is as follows: The whistle is placed between the lips or lips and teeth, or is held against the lips when puckered, as in the preparatory step in the ordinary whistling, with the air chamber or cavity *g* next to the mouth or teeth. The operator then blows through the device with a much less volume of air than is required in whistling in the ordinary manner. The current of air passes out through the hole *c* into the enlarged opening *d*, and produces the proper vibrations of the air to make a clear whistling sound, which is or can be controlled by the movements of the tongue, the muscles of the mouth and throat, together with the volume of air and the velocity with which it

is forced through the hole *c* by the effort of the operator, as in the ordinary manner of whistling.

By the laws of air vibrations to produce musical sounds, a large long tube or cavity produces deep full tones, while a small shallow tube or cavity produces high thin tones; but by the use of my device a good whistler, by a skillful use of the muscles of the mouth, tongue, and throat, and the breath, is enabled to vary the pitch, tone, and volume of sound by the same whistle; and, furthermore, my device enables the whistler to produce musical sounds with greater facility, while those who cannot whistle a tune are enabled to do so with my device if they can but give the proper rhythmic propulsion to their breath.

Having thus described my invention, what I claim, and desire to secure by Letters Patent, is—

1. A whistle, or device to aid in whistling, provided with an aperture or apertures, such as described, and adapted to be held by or within the lips of the operator, the tones or musical sounds of varying pitch being produced as in the ordinary manner of whistling.

2. A whistle composed of a block, disk, plate, or other suitably-shaped piece of metal, glass, or other material having a hole through it, formed as described, so as to produce the proper vibrations in the air blown through it to make a whistling sound, which can be varied by the muscular action of the mouth, tongue, and throat, and by the breath, as in the ordinary manner of whistling, so as to produce all the notes of the musical scale, as set forth.

3. A block, disk, plate, or any suitably-shaped piece of metal or other material, having therein or therethrough one or more holes so formed that when the air or the breath is forced through it the proper vibrations of the air will be made to produce a whistling sound, which can be perfectly controlled by the muscles of the mouth, tongue, throat, and volume of air exhaled from the lungs to produce the notes of the musical scale, as set forth.

4. A whistle composed of a block, disk, plate, or any suitably-shaped piece of metal, glass, or other material having two or more holes in or through it of such shape as when adjusted to the mouth or lips and air being blown therethrough will produce two or more distinct or independent tones, each hole producing a tone differing in pitch from any one of the other holes, which can be varied by the muscular action of the mouth, tongue, and throat, and breath, and made to produce the notes of the musical scale, as set forth.

5. A whistle composed of a block, disk, plate, or any suitably-shaped piece of metal, glass, or other material, having a hole through it, one end of which is smaller than the other, with a smooth sharply-finished edge, through which the air or the breath being forced a whistling sound will be produced, which can

be controlled by the mouth, tongue, throat, and breath, so as to produce the notes of the musical scale, as set forth.

6. In a whistle composed of any suitably-shaped piece of metal, glass, or other material, the combination of the chambers *h* and *g* with the hole *c*, having at one end the flaring edge *d*, and the other end, *o*, finished with a smooth square shoulder or edge, as and for 10 the purpose set forth.

7. A whistle composed of a block or cylinder of metal or glass, having a diaphragm or partition, *a*, therein, said diaphragm being provided with a central perforation, *c*, which terminates in the cavities or chambers *g* and *h*, 15 as and for the purpose set forth.

HENRY C. SWAN.
